(57) **CLAIM**

I claim the ornamental design for a dental protruor, as shown and described.

DESCRIPTION

FIG. 1 is a perspective view of a dental protruor in accordance with the present invention.

FIG. 2 is a front view of the dental protruor of FIG. 1.

FIG. 3 is a rear view of the dental protruor of FIG. 1.

FIG. 4 is a right-side view of the dental protruor of FIG. 1.

FIG. 5 is a left-side view of the dental protruor of FIG. 1.

FIG. 6 is a bottom view of the dental protruor of FIG. 1; and,

FIG. 7 is a top view of the dental protruor of FIG. 1.

All broken lines shown in the drawings are for environmental purposes only and form no part of the claimed design.
